ELECTRIC SWITCH

Sidney Unger, New York, N. Y., assignor to E. A. Laboratories, Inc., Brooklyn, N. Y., a corporation of New York

Application April 10, 1946, Serial No. 660,949

6 Claims. (Cl. 200—168)

1

This invention relates to electric switches and in particular to a switch having completely enclosed contact means.

It is a principal object of the invention to provide a compact switch of relatively small size, in which the contacting elements are protected from the external atmosphere.

It is an object of the invention to provide a switch having an imperforate body portion provided with a flexible neck portion mounting a rigid contact member for cooperation with fixed contact means within the said body.

It is a further object of the invention to provide an electric switch having contact means which are normally completely enclosed, but which are accessible for replacement or inspection.

It is yet another object of the invention to provide a switch in which the contacts are disposed within a gastight chamber which may have an interior atmosphere having a gas pressure greater or less than normal atmospheric, as desired.

It is another object of the invention to provide a switch of inexpensive construction which will function over long periods of time with freedom from operational difficulties.

This application is a continuation in part of my copending application Serial No. 601,613, filed June 26, 1945, now Patent Number 2,401,390, entitled "Retractable lamp structure."

Other features and advantages will hereinafter be described.

In the accompanying drawings:

Fig. 1 is a top plan view of a presently preferred embodiment of a switch incorporating the present invention;

Fig. 2 is a side elevation in section on lines 2—2 of Fig. 1;

Fig. 3 is a plan section on lines 3—3 of Fig. 2;

Fig. 4 is a vertical elevation taken on lines 4—4 of Fig. 2; and

Fig. 5 is a sectional elevation showing a second method of securing the flexible chamber neck to the switch chamber.

Referring to the drawings, the switch 10 includes a supporting base or the like having an angle bracket 11. Brazed, soldered, or otherwise secured to a leg 13 thereof is an imperforate tubular housing 12 within which is located a contact member 14. The leg 13 forms a closure for the end of said housing. Plates of insulation material 15, 16 serve to insulately support the contact on the leg 13, and the illustrated rivets, screws or the like serve as electrical con-

2

nection means between the contact and a soldering lug or similar terminal 17.

The insulators 15, 16 are preferably of yieldable material such as synthetic or natural rubber or rubber compounds; the rivets or screws cause the opposed surfaces 18, 19 respectively of the terminal and contact to compress the insulators to effectively seal the openings 20 through the bracket leg 13 against leakage.

The opposite end of the cylindrical chamber 12 receives or telescopes with respect to a collar 22 provided at the end of a flexible neck, which may be a tubular metallic bellows 23 of conventional form. The collar 22 may be soldered or otherwise secured to the chamber 12, or, as shown in Fig. 5, may be screw-threadedly affixed thereto by relatively fine threads. In such form, it is desirable to interpose a gasket 23' between the last convolution of the bellows and the end wall 20 of the chamber. To the opposite end of the bellows there is affixed an actuator plate 24 which completely closes the end of the neck. Said plate 24 is hereinafter referred to as an actuator, and is provided with an enlarged opening which receives a resilient or deformable insulating bushing 25 provided centrally of the bellows. A contact bar 26 having a contact button 27 in operative position with respect to the contact 14 is secured to the insulator 25. It will be noted that said contact bar has an enlarged head 28; a screw 29 passing through the terminal lug 30 will, when tightened, compress the insulator 25 to seal the opening through the actuator plate 24.

The switch housing is thus completely sealed against the external atmosphere and the housing may be evacuated to a suitable subatmospheric pressure or may contain an inert gas under any desired pressure.

Riveted or otherwise secured to one face of the angle bracket 11 is a pivot support plate 31 which preferably extends parallel to the housing 12, and which at its opposite end has an opening serving as a bearing for a pintle 32 projecting from an ear provided on the actuator 24. To the opposite side of the angle bracket 11 there is affixed a member 33, having two divergent plate portions. Plate 34 thereof extends parallel to the housing 12 and is provided with an opening which receives a pintle 35 extending from the opposite side of the actuator 24. Pursuant to this construction, the actuator may be rotated clockwise or counterclockwise about its respective pintles, and the flexible neck will distort so that its axis is angularly displaced with respect to the axis of the housing 12. Secured to the plate 31 and ex-

tending across the structure is a stop 36 which, see Fig. 4, serves to limit the extent of clockwise rotation of the actuator 24.

It is considered preferable to have the switch positively biased in either closed or open circuit position. Accordingly, an upper plate 37 of the member 33 extends forwardly of the housing 12 and terminates in a tip 38. Similarly the actuator 24 has a projecting end 39 having a tip 40 substantially in registry with tip 38. A coil spring 41 fits over the respective tips and is held in position thereon. As is apparent from Fig. 2, the spring 41 tends to rotate the actuator 24 into clockwise rotation, whereby the contact 27 will be continuously in engagement with the contact 14. An arm 42 on the lower end of the actuator 24 typifies any structure which can be grasped or otherwise engaged to rotate the actuator 24 in counterclockwise direction in order to break the contact.

It will be obvious that with the same initial structure, the switch can be converted to a normally open circuit device by mere reversal of the position of the contact 14, in which event the spring induced clockwise rotation of the actuator 24 would hold the respective contacts apart.

In the Fig. 2 embodiment, the contact bar 28 may be removed for inspection or replacement of its contact by sufficiently loosening the screw 29 to permit the rubber bushing 25 to decompress, then working or twisting the contact bar assembly to disengage the shoulders of the bushing from the wall of the actuator 24. The contact 27 and, of course, the head 28 of the contact bar are suitably smaller in diameter than the opening in member 24.

The pivot support plates or members 34 and 31 are sufficiently springable to permit them to disengage with the pintles of the actuator plate. Then, grasping the actuator 24 to extend the bellows to a position at which the actuator 24 clears the ends of the plates 34 and 31, a switch of the Fig. 5 type can be disassembled by unscrewing the bellows from the housing. The threaded length of the collar 23 of Fig. 5 is such that with the bellows in relaxed condition, the threads will engage with those in housing 12 before any conflict of actuator 24 with the pivot support plates. After the threads engage, the bellows can be forcibly extended to permit the complete assembly.

Whereas the invention has been described by making a fully detailed reference to a certain presently preferred embodiment, such detail of description is to be understood in an instructive rather than a limiting sense, many changes being possible within the scope of the claims hereto appended.

I claim:

1. An electric switch comprising a frame, a cylindrical chamber carried by said frame, and having a flexible bellows extending from one end of said chamber, said chamber and said bellows being closed at their respective free ends; an actuator plate secured to and closing one end of said bellows; means on said frame for pivotally mounting said actuator arm; spring means carried by said frame for rotating said actuator plate to flex the said bellows in one direction; a contact fixed within said chamber, and a second contact fixed to the closed end of said bellows and extending into said chamber in operative relationship to said first contact.

2. An electric switch comprising a frame, a tubular chamber affixed thereto, a portion of

said frame forming a closure for one end of said chamber; a tubular member having a plurality of corrugations at right angles to the axis thereof secured to the wall of said tubular chamber and extending axially thereof; an actuator member secured to the free end of said corrugated member transversely thereof and forming a closure therefor; spring mount means provided on said frame externally of said chamber; spring mount means provided on said actuator member; a spring common to said two spring mount means to exert a rotative force on said actuator; contact means fixed within said chamber; and complementary contact means supported on said actuator member and extending into said chamber in operative relationship to said first named contact means.

3. An electric switch including a frame, a tubular chamber affixed thereto, a portion of said frame forming a closure for one end of said chamber; an end of said tubular member having a plurality of corrugations formed peripherally about its wall to impart flexibility thereto, the free end of said member being closed by means including a distortable, removable plug of insulation material; a contact insulatedly fixed within said tubular chamber; a second contact carried by said distortable insulation means and extending into operative relationship with respect to said fixed contact; and means for conjointly securing said second contact to said distortable plug and to expand said plug to afford sealing relationship between said plug and the closure means of said corrugated tubular member; the maximum diameter of said second contact being less than the minimum effective diameter of said closure plug when the same is in expanded status.

4. An electric switch including a frame, a tubular chamber affixed thereto and having one closed end; an expansible bellows screw-threadedly secured to said chamber in gas-tight relation therewith; a contact in said tubular chamber; a second contact secured to an end wall of said bellows and extending into said chamber in operative relation to said first contact; an actuator secured to said bellows end; and pivot plate means on said frame removably pivotally engaging said actuator; the position of said pivots relative to the normal unexpanded length of said bellows being such that upon disengagement of said pivotal plates and forcible expansion of said bellows, the latter may be rotated to be unscrewed from said tubular chamber without conflict of said actuator with respect to said pivot plates.

5. An electric switch, comprising a frame, a rigid chamber affixed to said frame, said chamber having one open end; a sleeve-like flexible bellows secured to and enclosing the open end of said chamber, and extending axially thereof; a plate pivotally mounted on said frame and closing the free end of said bellows; a spring acting on said plate for rotating the same and normally biasing said bellows out of axial alignment with said chamber; a contact fixed within said chamber; a second contact extending into said chamber from the bellows end thereof and movable according to rotation of said plate into or out of engagement with said first contact; a lever extending from said plate for rotating the same; and stop means fixed to said frame and engageable with said plate to limit rotation thereof in one direction.

6. An electric switch including a frame, a closed-ended rigid chamber carried thereby, the wall at one end of said chamber being formed
